FUEL INJECTOR MECHANISM

Gardiner M. Rogers, Ithaca, N. Y.

Application July 3, 1946, Serial No. 681,329

3 Claims. (Cl. 103—41)

1

This invention relates to an improvement in fuel injectors for internal combustion engines, particularly of the Diesel type and specifically to various improvements particularly applicable to a fuel injector embodying the essential principles of my application Serial No. 608,588, filed August 2, 1945. The injector shown in said application differs from the usual jerk pump in several ways, the principal ones being: (a) the beginning of injection is determined by opening of a delivery port leading from a helix cavity to the atomizing nozzle, termination being effected by opening of the helix cavity to a spill port, and (b) provision of a simple and accurately calibrated pressure control valve communicating with the metering cavity for draining off a certain quantity of fuel from the pressure space of the pump over and above what is needed for a particular charge, thus making each injection a function of plunger speed and porting adjustment but without limiting the charge to a definite amount of plunger displacement.

In the construction outlined above, the delivery port and spill port were so related to the injection initiating and completing helix and cavity portions of the plunger that all the adjustment from "no injection" to "full load injection" had to be accomplished by relative rotation of the plunger and its cylinder through less than half a circumference. One improvement hereof (indicating one object) is to provide, in a non-positive displacement injector, separate delivery and spill initiating control edges (helices) so that the adjustment from "no injection" to "full load injection" can be accomplished by relative adjustment of the plunger and cylinder through a much greater angle than half a circumference, for example through nearly a full circumference, whereby the slope of the control helix edges may be greatly lessened and the sensitiveness of the injector to a given engine regulation adjustment of the fuel racks will be less pronounced.

A concomitant object is to provide an improved fuel control helix arrangement in an engine-power-operated pump and valve plunger and cylinder assembly operable as a controlled pressure non-positive displacement injector whereby speed regulation may be accomplished very gradually, particularly at idling and cranking speeds, by relative rotational adjustment of the pump plunger and cylinder.

A further object is to provide an improved pressure regulating valve for a controlled pressure fuel injector pump, and specifically a valve formed by a ball and an annular spring normally

2

but yieldably holding the ball in sealing relation to a relief port of the pump pressure chamber, which spring is never subject to localized wear and operational stress but operates continuously to change position in the valve assembly.

A further object is to provide an improved atomizing nozzle assembly for a fuel injector, wherein the atomizing nozzle orifices can be more simply formed than by use of the usual drilling operations; will be subject to easy cleaning and wherein the essential operating parts of the nozzle are capable of being permanently locked in the desired relative positions insuring that all injectors of a set will have uniform atomizing operation.

Further objects include provision of a self valving plunger and cylinder type controlled pressure injector pump in which the possibility of material axial distortion of the cylinder by injection impact force is reduced.

Other objects and features of the invention will become apparent from the following description of the exemplary embodiment shown by the accompanying drawings wherein:

25 Fig. 1 is a central longitudinal assembly view of a unit injector incorporating principles of the present invention;

Fig. 2 is an enlarged fragmentary sectional detail view of the atomizing nozzle taken along the line 2—2 on Fig. 1;

Figs. 3 and 4 are cross sectional detail views of the nozzle mechanism as indicated by the lines 3—3 and 4—4 on Fig. 1;

35 Fig. 5 is an enlarged transverse cross sectional detail view of the controlled pressure regulating valve taken along the line 5—5 on Fig. 1;

Fig. 6 is an enlarged side elevation of the injector pump plunger according to Fig. 1;

Fig. 7 is a development view of the valving portion of the plunger showing the control helices and associated recesses formed on the plunger, but omitting the fuel supply ports leading to said recesses from within the plunger;

40 Fig. 8 is a development view similar to Fig. 7, showing certain modifications in the valving or control helix portions of the plunger; and

Fig. 9 is a central sectional view taken on divergent radial planes as indicated at 8a—8a and 9a—9a respectively, Fig. 8.

45 The mechanism shown by Fig. 1 is on the order of that shown by my said prior application, wherein an engine operated plunger piston 1 in a pump cylinder 2, usually referred to as a bushing, is reciprocated in a manner to draw fuel from a fuel cavity or reservoir 3 through suitable ports

and deliver the fuel to a nozzle mechanism generally shown at 4 under very high pressure in proper relationship to the compression stroke of the engine cylinder served. The unit injector as shown herein includes a main body member 5 receiving, in a counterbore 5' of the body, a reduced diameter upper portion of the pump cylinder or bushing 2. The body 5 is threaded as at 6 for engagement with a sleeve-like nut 7 which enters the associated engine cylinder as through the cylinder head water jacket and supports the nozzle mechanism 4 in communication with the combustion space of the cylinder. The sleeve-like nut 7 has a shoulder at 8 for engagement with a suitable gasket (not shown) around an opening in the cylinder head, and a reduced diameter portion 9 which fits a smaller bore in the cylinder head and is held therein by suitable means (not shown) which engages the body 5 and forces the shoulder 8 against the cylinder head.

The fuel cavity or reservoir 3 is formed as an annular space between the bushing 2 and sleeve-like nut 7, said space being sealed at its top end partly by an upper shoulder 10 of the body 5 against which the bushing 2 is seated when the sleeve-like nut is threaded to the body at 6. The lower end face 11 of the bushing 2 abuts a coaxial base piece in the form of a recessed block 12. The base piece is one of a plurality of stacked centrally apertured injector parts fixedly supported in and by the sleeve nut as will be described later.

The fuel cavity 3 is supplied with liquid fuel through a supply pipe 15 leading to a filter chamber 16 containing a filter unit 17, the outlet of the filter communicating with a supply duct 18 in the body 5 entering the upper end of the fuel cavity.

The bushing 2 has a single transverse bore 20 leading to the lower end or pressure chamber portion P of the cylinder bore 21 of the bushing just below the lower end of the plunger when the latter is in its raised or inactive position. The lower end of the cylinder 21 is closed by a central imperforate portion of the base piece or block 12. The single port 20 forms both a supply port and spill port for the valving mechanism of the injector plunger, wherefore the compression resisting cross section of the bushing is reduced a minimum amount to provide for supply and spill. Above and diametrically opposite from the port 20 is a lateral delivery port 23 intersecting a vertically extending or axial bore 24 which is open at its lower end only for communication with an annular trough or channel 25 on the top side of the block 12. The latter has an oblique duct 26 leading centrally of the assembly to a check valve chamber 27. The check valve chamber is formed in a circular valve body 28, one of the stacked parts mentioned, seated by engagement with the block 12 against an upper flanged portion 30 of a nozzle fitting 31, the lowermost of the stacked parts. The valve body 28 and said flange fit snugly in respective parts of a central through bore 22 in the lower reduced diameter portion of the sleeve nut 7. The lower or reduced diameter main portion of the nozzle fitting 31 projects beyond the lower end of the sleeve nut. The nozzle fitting and valve body 28 have central communicating bores 34 and 35 respectively. The bore 34, containing a suitable main spring closed check valve plug 36 which, between injection strokes of the plunger, closes the bore 35 against flow of fuel from the delivery duct toward the

nozzle. In event the valve plug 36 refuses to close as by reason of accumulation of foreign matter on the valve seat, combustion pressure may force combustion gas back into the injector through the delivery ducts, and to prevent that from occurring the valve chamber 27 may be provided with an apertured check valve disc 39 which floats vertically in the chamber 27 and can be forced by such back pressure of gas from the combustion space against the flat face of the body 12 so as to seal off the delivery duct.

The lower end of the bore 34 of the nozzle fitting 31 is partially closed by a screw 40, the head portion 41 of which has a conical face 42 seating against a generally conical face 43 on the lower end of the injector fitting. The conical face of the screw head forms partial wall portions of respective atomizing nozzle orifices 44. The remaining walls of the orifices 44 are formed as grooves or channels in the conical terminal face 43 of the nozzle fitting. Thus, when the screw is in the position shown, the channels are closed except at their ends by the conical face 42 of the screw head but they may be wholly opened for enabling easy cleaning as with a brush or air blast, by withdrawal of the screw from its illustrated position.

The screw 40, as brought out particularly by Fig. 3, has its threaded shank flattened as at 46, at least on one side (shown oppositely flattened) so that fuel can pass downwardly freely along the shank of the screw to an enlargement of the threaded bore indicated at 47 above the conical face 42 of the screw head and generally closed thereby. It is important that each individual orifice 44 be maintained accurately within very close tolerances and, assuming the channels have been accurately formed, the actual cross section of each of the orifices may be regulated to a slight extent by pressure of the conical face 42 against the complementary end face of the nozzle fitting. To adjust the pressure between the conical faces, the screw may be turned to head seating position as by engagement of a suitable tool with a non-circular recess 50 in the screw head. The preferred form of locking detent for the screw comprises a locking rib 52 at one side of the nut head designed to enter a selected one of a series of complementary grooves 53 formed on the head. The grooves may be formed simply as parallel serrations on the head. The locking detent 52 is in the form of a spring arm which extends from a longitudinal recess 54 in one side of the nozzle fitting 31, being staked into place as by indentations 55, Fig. 3, of the side walls of the channel 54 overhanging the rectangular shank of the detent. The free portion of the detent beyond the lower end of the sleeve nut 7 constitutes the spring arm of the detent. While the screw can be turned to various positions without removing the detent, the latter, principally by reason of the short length of the free portion, is fully effective by engagement with the notches in the screw head to maintain the setting of the screw against being jarred out of position by engine vibration. The detent arm is a fixed part of the nozzle fitting and the fitting, screw and detent can be withdrawn from the sleeve as a unit without disturbing the adjusted seated position of the screw head.

The pump plunger is adjusted as usual for engine regulation by a gear 57 keyed to the plunger and a cooperating fuel rack 58. The lower or valving and piston portion of the plunger has three sets of cylindrical lands designated 60, 61

and 62 accurately fitting the smooth cylindrical bore 21 of the bushing. The lands 60 and 61 are separated from each other by a neck or reduced diameter portion 63 on the plunger to provide a spill helix recess S. The lands 61 and 62 are similarly separated by a neck or reduced diameter portion 64 to provide a separate delivery helix recess D. The upper edge 65 of the land 60 has relatively inclined or helix portions 65a so as to provide a regulatable helix in relation to the combined spill and supply port 20. Similarly, the upper edge 66 of the land 61 has inclined or helix portions 66a which function in relation to the delivery port 23 leading to the nozzle. The neck or reduced portion 64 is long enough to provide for continuous communication of the pressure space P with the pressure control or regulator valve 10 leading to the reservoir or fuel cavity 3. Both helix cavities are, as usual, constantly connected with the cylinder pressure space P through axial and transverse bores 67 and 68—69 respectively in the plunger.

When the lower end of the descending plunger cuts off the combined spill and delivery port to trap fuel in the pressure space P at the lower end of the cylinder 21, the fuel from the pressure space is free to enter both helix recesses D and S. It should be noted that the longitudinal dimensions of the lands 60 and 61 and axially spaced relationship of the ports 20 and 23 are such that the land 61 covers the delivery port 23 just before the supply port 20 is covered by the lower end of the plunger to trap fuel in the pump. Thus, during the initial part of the stroke, no fuel is delivered to the nozzle through the spill helix recess S although that recess uncovers the delivery port. If desired, a small quantity could be delivered from the recess S as a preliminary injection charge to assist in minimizing detonation. Communication of the pressure space P with the delivery duct 24 results from the further downward movement of the plunger necessary for the top edge of the land 61 to uncover the delivery port 23. Prior to the time the delivery helix 66 uncovers the delivery port 23, the fuel trapped in the space P is free to pass upwardly through the plunger to the delivery recess D where a desired amount of pressure is maintained by a fuel pressure regulating valve assembly 10, Figs. 1 and 5. The regulating valve acts, throughout the active stroke of the plunger 1, to bypass a certain percentage of the volume output of the pump to the fuel cavity 3.

The inlet port of the valve 10 is a radial passage 71 in the wall of the bushing 2 leading from the cylinder bore 21 to a counterbore 72 in the bushing. A hardened smooth surfaced metal ball 73 forms the plug for the regulating valve and is maintained normally in sealing relation to the port 71 by a continuous annular spring 74 encircling the bushing at a receiving channel 75 formed peripherally of the bushing and on a somewhat smaller diameter than the inside diameter of the ring. The opposite side walls of the channel 75 are spaced from the marginal edges of the ring a sufficient distance so that the ring is free to turn in the recess. The ring rests against the bushing at the side of the channel 75 opposite the inlet port (see Fig. 5) so that the ring is always somewhat eccentric to the bushing. The ring is forced into somewhat more eccentric position at one side of the bushing whenever the ball 73 is forced off its seat by fuel expressed from the pressure chamber through the bores 67, 69 of the plunger and the metering recess D to the relief port 11. As fully

explained in my application Serial No. 608,588, filed August 2, 1945, the valve 10 may be made by reasonably inexpensive manufacturing methods precisely to maintain a desired degree of pressure in the pressure space and delivery duct. Thus all the injectors of a set may be provided with the pressure control arrangement illustrated to insure delivery of fuel to the individual cylinders at the same pressure. That is important because regardless of the amount of displacement of the plunger in the cylinder 21, the amount of fuel delivered to the nozzle is solely a function of time, the pressure setting of the regulating valve and the size and characteristics of the orifices in the nozzle, and is not simply a function of piston displacement regardless of speed as in the ordinary jerk pump.

In addition to forming the channel 75 less wide than the axial width of the spring 74, said 20 ring has, substantially midway between its horizontal edges, a slight groove 77 in which the ball 73 bears against the ring. The groove, in addition to holding the ring in spaced relation to the side walls of the channel 75, increases the bearing contact between the ball and the ring and minimizes wear on both the ring and ball. It has been repeatedly observed that with 25 the ring and ball relationships shown by Figs. 1 and 5, the ring turns progressively always in the same direction although the counterbore 72 for the ball as well as the port opening (bore 71) are formed, as nearly as possible, strictly diametrically of the bushing 2.

It is known that the ball is spun about its center during operation of the injector, the 30 evidence being that the ball, when removed from service, shows no signs of localized wear but does show a complete and uniform color change due evidently to subjection to heat of rapid oil film travel past it from the port and probably polymerization of oil thereon. Although originally highly polished, the ball is uniformly brown after a relatively short period of service. It may be that the ball rotates unidirectionally due to the manner in which the fuel is forced from the relief port 71 and, therefore, frictionally drives the ring 74 in the central trough 77 at which the ball engages the ring. Previously, when no such guiding groove for the ring was provided and the travel of the ring axially of the assembly 35 was limited only by a recess corresponding to that at 75, Fig. 1, the ring, probably due to edge friction against the sides of the retaining channel, could not be depended upon to move progressively and thus successively present different surfaces to the ball. Another theory is that the ring, during subjection to engine vibration, tends, for unknown reasons, constantly to travel unidirectionally circumferentially of the bushing 2 40 on which it is supported and is simply enabled so to travel by the lesser degree of braking friction afforded by the present construction.

With the arrangement of combined supply and spill port 20 and delivery port 23 with relation to the spill and delivery helices shown and as 45 brought out more clearly in the development view, Fig. 7, the operation during descent of the plunger from the inactive position shown on Fig. 1 is as follows:

Assume, for example, that the plunger is so 50 adjusted by the fuel rack 58 that the delivery port is located relative to the helices for relative travel along the line X and that the supply and spill port 20 is located for relative travel along 55 the line X' (180° apart). Thus, in the inactive

or raised position of the plunger, the supply and spill port (at 20x, Fig. 7) is uncovered by the lower land 60 and the delivery port, at position 23z, lies above the helix edge 65 but below the lower edge of the land 61, and thus is open. Downward travel of the plunger causes the land 61 to close the delivery port before the land 60 closes the supply port and thereupon both ports will be closed until the plunger has lowered to bring the helix edge 66 into cracking relation to the delivery port as at 23x'. In that descended position of the plunger, the relationship of the spill port (see 20x') to the spill helix 65 is such that shortly after opening of the delivery port the spill port will be opened by the horizontal portion of the helix 65 to terminate injection. The illustrated relative position of ports and plunger helices is an idling or cranking regulating adjustment of the plunger and it will be seen that, with the developed plunger surface moved further to the right (such port and helix relationship not illustrated), the delivery port will be opened earlier during the downward stroke of the plunger, causing injection of longer duration. A "no injection" adjustment of the plunger is illustrated in Fig. 7 by the relationship of ports and helices brought out by comparison of port positions 20y and 23y as though moved along the lines Y and Y' respectively. In that adjustment, a horizontal portion of the spill helix 65 opens the port 20 as before but, in this case, simultaneously with the delivery port opening operation of a horizontal portion of the helix 66. The concavity of the helix edge 65 in the zone 65a is in order to obtain an extremely gradual increase of fuel from "no injection" relative position of helices and ports toward initial fuel delivery relative position. Relative positions of ports and helices shown by the relatively reversed positions 20z and 23z (along lines Y' and Y respectively) further illustrate the coaction of the sloping surface portions of both helices in an intermediate fuel regulating position of the plunger. The same effect can be had by a less gradual dropping off of the helix 66 from its "no injection" or horizontal high portion downwardly along the slope as indicated, for example, by the broken line 66b. In the event the less gradual slope 66b is used, then a non-concave slope would be used on the spill helix in the zone 65a. The helix relationships are illustrative only since, as well known in the art, helix designs are varied as required for most efficient engine operation. Sloping of the control edge 65 for spill enables less slope to be used on the delivery helix.

Since the delivery helix may extend for a substantial distance around the plunger greater than 180°, the slope of both helices may be much less than in the case such as illustrated by my copending application, wherein the delivery port and spill port are opposite each other and less than half of the circumference of the plunger must be used for spill and delivery respectively.

Figs. 8 and 9 illustrate first that only one of the cavities D' or S' needs to have an inclined edge for fuel regulation adjustment by turning of the plunger. The fuel adjustment from "off" to "maximum speed" is governed by the inclined control edge portion 166a of the cavity edge 166. The entire upper limit (edge 165) of the land 160 is shown as horizontal with the exception of a short depressed portion 165b which may be termed a "stop loop." The stop loop, during descent of the plunger, effects open-

ing of the spill port, diagrammatically indicated in an associated position at 120x, when the delivery port at 123x is still closed by the land 161. The stop loop affords an opportunity for the fuel in the pressure space P to begin to be bypassed to the fuel reservoir well before the delivery port is opened by the descending plunger at the high horizontal portion of the edge 166.

In relatively large injectors, the plunger displacement is sometimes such that the rate of fuel bypass discharge through the spill port is insufficient to prevent delivery of some fuel to the nozzle in the "off" position. In such cases, an unused portion of the cavity D' can have a by-pass channel formed in the land 161 as at 171 leading to the cavity S' to provide a direct path for fuel from the cavity D' to the spill port in addition to that provided by the center bore 67 (see Fig. 6) and the cross bores 68 and 69. When such alternate and more direct path is available, there is no likelihood of fuel being forced to the nozzle in the "off" positions of the plunger. Alternatively, the helix cavity D' may terminate between the high and low portions of the helix edge 166a so that in the "off" position of the plunger the delivery port cannot be unsealed by the cavity D'. A suitable circumferential portion of the cavity may thus be blocked off within the limits of the dimensional indication 170 on Fig. 8.

Figs. 8 and 9 also illustrate provision of a preliminary injection relief extension of the delivery helix for the purpose of reducing detonation. Detonation is most troublesome during idling and cranking speeds. The relief may be formed by a region of slightly reduced diameter on the plunger land 161 as indicated at 166b on Fig. 9, at the idling speed control portion only of the edge 166a. The relief is very slight, being for example about .0007" in a plunger having a valve land diameter of about .275". The preliminary injection relief portion 166b of the delivery helix functions slightly to open the delivery port to start injection during the descent of the plunger earlier than it normally would be opened by the main inclined portion of the helix. Thereby, a small amount of fuel is caused to be injected into the cylinder during the compression stroke ahead of the main charge. When the main charge enters the cylinder, it is ignited by the already burning preliminary injection charge, thus greatly reducing or eliminating detonation.

An illustrative relative idling position of delivery port and spill port is given on Fig. 8, wherein 123y indicates the partially opened position of the delivery port just before the spill port at 120y opens to terminate injection. It is apparent from the showing that the preliminary injection period which commences as soon as the delivery port intercepts the relief zone 166b of the plunger is followed by a main injection period of relatively short duration.

For adjusting and operating the plunger 1, a conventional arrangement is shown. Fuel adjustment comprises the adjusting gear 57 and rack 58. The gear is supported between the top end of the bushing 2 and a shoulder 81 within the body. The gear is, in effect, splined to the upper end portion 82 of the plunger at a flat surface portion 83 thereof. For reciprocating the plunger, the top end thereof is engaged by an inturned flange 84 of a follower guide 85 slidably in a smooth bore 86 of the body 1 and held against rotation by a removable key pin 87 on the body 5, which pin also acts as a limit stop for the follower

guide in a well known manner. Above the somewhat enlarged head portion of the plunger is a follower or tappet piece 88 secured to the follower as by a cross pin 89. The engine rocker arm 90, through a suitable roller 91, operates the plunger against the opposing force of a plunger return spring 92 around the follower and supported against the top face of the body 1. The lower end of the spring holds the key pin 87 in place as will be evident.

I claim:

1. A fuel injector pump of the reciprocating type, comprising a cylinder which is closed at one end and a plunger fitting the cylinder to form a pressure chamber at the closed end and retractable to a predetermined position away from the closed end to commence its pressure stroke, a supply port intersecting the cylinder beyond the end of the plunger in its retracted position, two axially spaced circumferentially extending valving cavities in the plunger continually communicating with each other and with the pressure chamber, a delivery port intersecting the cylinder and located so as to be opened by one of the cavities to commence injection, the other cavity being located so as later to open the supply port for fuel-spill to terminate injection and restricted fuel-venting means connected with the pressure chamber during the pressure stroke of the plunger and controlling the injection pressure of the pump.

2. An engine fuel injector reciprocating pump comprising a cylinder and a plunger fitted thereto and forming with the cylinder a pressure chamber at one end of the plunger, said plunger being movable from a full retracted position to a full advanced position, combined supply and spill port means intersecting the pressure chamber and located beyond the end of the plunger in its full retracted position, two axially spaced circumferentially extending valving cavities in the plunger communicating with each other and with the pressure chamber, a delivery port intersecting the cylinder in position to be opened at one part of the plunger stroke by the cavity which lies the more remotely of said end of the plunger to commence injection, the other cavity during another part of the same stroke opening the supply and

spill port means to terminate injection and restricted fuel-venting means connected with the pressure chamber during the pressure stroke of the plunger and controlling the injection pressure of the pump.

3. A fuel injector pump of the reciprocating type, comprising a cylinder which is closed at one end and a plunger fitting the cylinder to form a pressure chamber at the closed end and retractable to a predetermined position away from the closed end to commence its pressure stroke, a supply port intersecting the cylinder beyond the end of the plunger in its retracted position, two axially spaced circumferentially extending valving cavities in the plunger continually communicating with each other and with the pressure chamber, a delivery port intersecting the cylinder and located so as to be opened by one of the cavities to commence injection, the other cavity being located so as later to open the supply port for fuel-spill to terminate injection, and a pressure-control restricted vent means for the pressure chamber including a port in the cylinder so located as to be open to said one cavity at such commencement of injection.
